UNITED STATES PATENT OFFICE.

STEPHEN B. MORSS, OF RAHWAY, NEW JERSEY, ASSIGNOR TO FREDERICK W. KEASBEY, OF MORRISTOWN, NEW JERSEY.

LAMP-BURNER.

SPECIFICATION forming part of Letters Patent No. 641,218, dated January 9, 1900.

Application filed August 24, 1899. Serial No. 728,320. (No model.)

To all whom it may concern:

Be it known that I, STEPHEN B. MORSS, a citizen of the United States, residing in Rahway, Union county, New Jersey, have invented certain new and useful Improvements in Lamp-Burners, of which the following is a specification.

The object of the invention is to produce an even flame and increase the quality of the light from the burner; and the invention consists in a combined wick-tip and extinguisher comprising a flange or ring adapted to rest upon a wick and having a guide secured to and depending from the same to direct its vertical movement when lifted by the wick.

The invention further consists in the novel details of improvement, that will be more fully hereinafter set forth and then pointed out in the claims.

Reference is to be had to the accompanying drawings, forming part hereof, wherein—

Figure 1 is a vertical cross-section of the upper portion of a lamp-burner embodying my improvements, and Figs. 2 and 3 are perspective views of the flange or ring and its guide.

In the accompanying drawings, in which similar numerals of reference indicate corresponding parts in the several views, 1 and 2 indicate the concentric tubes of a central-draft-lamp burner between which a cotton or other fibrous wick 3 is adapted to pass. The tubes 1 2 constitute the wick casing or guide in a central-draft-lamp burner, which may be of suitable or well-known construction and which it is not necessary to more fully illustrate and describe, it being understood that any suitable means may be provided for raising and lowering the wick.

4 is a perforated thimble, cone, or air-distributer, which may be of suitable or well-known construction and adapted to fit within the tube 1, being shown provided with a depending portion 4^a for this purpose, so that it may rise and fall in said tube, receive air therefrom, and distribute it to the flame produced at the top of the wick in well-known manner.

5 is a flange or ring extending over the wick 3 and adapted to rest upon the tops of tubes 1 and 2 when the wick 3 is turned down to

thus act as an extinguisher of the flame, and the flange or ring 5 has a guide 6, secured to and depending therefrom, which is shown in the form of a tube or sleeve adapted to fit 55 within tube 1, so as to rise and fall within the same. The size and shape of the part 4^a of the thimble or air-distributer 4 are such that it can fit within the guide or sleeve 6, and the thimble or air-distributer is also shown provided with an annular rib or flange 4^b to rest upon the flange or ring 5, whereby the thimble or air-distributer will partake of the up-and-down movement of flange 5 and its guide 6, and during such movements the latter is 65 guided in tube 1. By preference I make the flange 5 of metal, and it constitutes a tip for the wick, which covers the upper surface of the same and protects it from the flame, and the guide 6 also protects the inner surface of 70 the wick from the flame. In order to allow the gases that generate at the top of the wick to freely pass away and mingle with the flame, the flange or ring 5 may be perforated, as at 5^a, which enables gases to pass through the 75 apertures from the top surface of the wick to the flame.

It will be understood that the thimble or cone 4 is supported upon the tubes 1 2 through the medium of the flange 5 and that as the 80 wick 3 is raised and lowered the flange 5, its guide 6, and the thimble or cone 4 will be likewise moved by it. By this means an even amount of air will be distributed to the flame at all times. When the wick is raised above 85 the tubes and lighted, the flame will burn upon the outer surface of the wick above tube 2, and the flange 5 will serve to keep the flame even or level on top, and the flange will also become heated, especially when made of 90 metal, and will serve to assist in vaporizing the oil at the top of the wick, which vapor will mingle with the flame and cause the flame to burn more brilliantly and evenly, as the carbon in the vapor thus generated adds to 95 the combustion of the oil drawn up by the flame. When the wick is lowered even with or below the tops of the tubes, the flange or ring 5 will act to extinguish the flame. The flange 5, furthermore, serves to prevent smoke 100 and odor from arising when the wick is lowered.

Having now described my invention, what I claim is—

1. A combined wick-tip and extinguisher comprising a perforated flange or ring adapted to rest upon a wick and having a guide secured to and depending from the same to direct its vertical movement when lifted by the wick, substantially as described.
2. A combined wick-tip and extinguisher comprising a metal flange or ring adapted to rest upon a wick and having a guide secured to and depending from the same to direct its vertical movement when lifted by the wick, substantially as described.
3. The combination of inner and outer wick-

casing tubes, and a wick therebetween, with a tip comprising a metal flange having a guide integral therewith and depending within the casing, substantially as described.

4. The combination of a thimble or air-distributer with a metal flange or ring adapted to rest upon a wick and having a guide secured to and depending from the same, and means for supporting the thimble or air-distributer above said flange, substantially as described. 25

STEPHEN B. MORSS.
